UNITED STATES PATENT OFFICE

94,062

DESIGN FOR A CONTAINER FOR CONFECTIONS

John J. Wilsdon, Shelby, Ohio, assignor to The Shelby Gum Company, Shelby, Ohio, a corporation of Ohio

Application December 28, 1933, Serial No. 50,243

Term of patent 14 years

To all whom it may concern:

Be it known that I, John J. Wilsdon, a citizen of the United States of America, and a resident of Shelby, in the county of Richland and State of Ohio, have invented a new, original, and ornamental Design for a Container for Confections, of which the following is a specification, reference being had to the accompanying drawing forming a part thereof.

In the drawing:

Fig. 1 is a perspective view of the new container in fully assembled and closed condition;
and

Fig. 2 is a similar perspective view of the container showing the upper closure flap pulled clear of the body.

I claim:

The ornamental design for a container for confections, substantially as shown.

JOHN J. WILSDON.
